SCREEN

Newenham A. Gray, Wausau, Wis., assignor to
 D. J. Murray Manufacturing Co., Wausau, Wis.,
 a corporation of Wisconsin

Application August 10, 1942, Serial No. 454,239

5 Claims. (Cl. 209—273)

The present invention relates generally to improvements in the art of classifying various materials by subjecting the mixed materials to pulsation of a fluid medium, and relates more specifically to numerous improvements in the construction and operation of pulsating screens, jigs, or the like.

An object of the invention is to provide improved pulsating classifying or screening equipment which is simple in construction and efficient in operation.

Numerous different types of so-called jigs or pulsating screens wherein separation or classification of mixed granular or fibrous materials is effected by causing repeated reverse flow or pulsation of liquid through a liquid-pervious bed or screen upon which the material being treated is disposed, have heretofore been proposed and used with varying degrees of success. While some of these prior devices have proven quite satisfactory for the purpose of treating a few readily separable mixed materials, most of them are relatively crude and inefficient in action as well as being complicated in structure. Many of the prior pulsating screen separators could not be readily adjusted to meet varying conditions of operation, without interrupting normal operation of the machines; and in addition, most of these prior mechanisms could not be quickly manipulated to provide for varying demands or capacity.

It is therefore a more specific object of the present invention to provide an improved pulsating screen unit which is simple and durable in structure, sensitive and highly efficient in operation, and flexible in its adaptations.

Another specific object of my invention is to provide an improved classifier for mixed granular or fibrous materials, comprising improved screening and pulsating units which are adapted to most effectively co-operate with each other.

A further specific object of this invention is to provide a new and useful hydraulic screen assemblage and mechanism for producing pulsation of liquid therein, wherein mechanical vibrations from the pulsating device will not undesirably affect the screening action, and in which the position of the screen may be varied without interfering with most effective operation of the pulsating unit.

Still another specific object of the invention is to provide an improved liquid pulsating device having frequency and amplitude varying means which can be adjusted without adversely affecting the operation of mechanism which is propelled or actuated by the pulsations, and which

device is capable of generating and transmitting pulsating waves of uniform rhythm and intensity.

An additional specific object of the present invention is to provide a pulsating material classifier having a minimum number of moving parts, maximum capacity with minimum power consumption, and wherein the cost of both manufacture and maintenance are reduced to a minimum.

Still another additional specific object of this invention is to provide an improved pulsatory classifying unit which may be advantageously utilized either singly or in multiple, for either 15 simultaneous or successive stage separation, and which will insure uniform and most efficient results under normal conditions of operation.

These and other objects and advantages of the invention will be apparent from the following 20 detailed description.

A clear conception of the several features constituting my present invention, and of the mode of constructing and of operating pulsating screen installations embodying the improvements, may 25 be had by referring to the drawings accompanying and forming a part of this specification wherein like reference characters designate the same or similar parts in the various views.

Fig. 1 is a vertical transverse section through 30 one type of my improved pulsating screen wherein in a single pulsator co-operates with four screen sections;

Fig. 2 is a top view of the screen portion of the unit shown in Fig. 1;

Fig. 3 is a rear view of the pulsator portion of the unit shown in Fig. 1;

Fig. 4 is a fragmentary horizontal section through the rear of the screen portion of the unit shown in Figs. 1 and 2;

Fig. 5 is a diagram showing units of the type shown in Figs. 1 to 4, inclusive, utilized in multiple;

Fig. 6 is a vertical transverse section through a modified type of screening unit provided with 45 a somewhat deeper siphon liquid discharge;

Fig. 7 is a top view of a further modified pulsating screen assemblage wherein a pair of pulsators each co-operate with a pair of screen sections;

Fig. 8 is a rear view of the modified improved screening assemblage of Fig. 7; and

Fig. 9 is a vertical transverse section through the assemblage of Figs. 7 and 8.

While the invention has been shown and described herein as being embodied in several spe-

cific types of pulsating screen assemblages especially adapted for the purpose of screening fibrous material in the paper industry, it is not my desire or intent to thereby unnecessarily restrict the scope or utility of the improvement.

Referring specifically to Figs. 1 to 5 inclusive of the drawings, each of the improved screen assemblages shown therein comprises in general a four section screening unit 10 co-operating with a common pulsating unit 11, and the two units 10, 11 being interconnected by means of a flexible liquid conducting tube 12, and the assemblages being adapted for use either individually or in multiple as shown in Fig. 5.

Each screening unit 10 consists of an approximately rectangular casing or screen housing 13 and a series of four interchangeably similar screen sections or plates 14 substantially horizontally disposed within the housing 13 and dividing the same into upper and lower chambers 15, 16 respectively, and the housing 13 may be provided with adjustable supporting feet 17 for effecting proper alignment or variation in inclination of the plates 14. The feed end of each housing 13 is provided with an elongated feed launder 18 which communicates with the upper screening chamber 15 over a feed weir 19, while the opposite overflow discharge end of each housing 13 is provided with a similarly elongated oversize discharge launder 20 having a rearwardly sloping bottom and communicating with an outlet 21. The lower pulsating chamber 16 which is disposed between the feed and discharge launders 18, 20 beneath the screen decks, also has a rearwardly inclined bottom 22 and is divided by transverse partitions 23 into four segregated pulsating sections which approximately correspond in area to the areas of the liquid pervious portions of the screen plates 14. The front ends of all of these pulsator sections of the chamber 16 are in open communication with an elongated siphon duct 24 extending longitudinally of the screening unit 10 and communicating with a collecting launder 25 over a series of vertically adjustable weir plates 26. These weir plates 26 should preferably be independently adjustable, and the overflow launder 25 has an outlet 27 near the feed launder 18 and a bottom 28 which is inclined toward this outlet.

The rear ends of all of the pulsator sections of the lower chamber 16 open into a distributing chamber portion 29 which communicates with the corresponding pulsator unit 11 through the flexible connecting tube 12, and entry of pulsating liquid to the several chamber sections or divisions is preferably controlled by means of adjustable streamlined gates 30 operable with the aid of hand levers 31. Since a definite hydraulic relation exists between the depth of the lower chamber 16 and the stroke of the pulsator unit 11, and the propagation of pulsating waves is a definite function of the pulsating frequency, the sloping bottom 22 of the housing 13 should be so pitched that the pulsating amplitude is transmitted uniformly to all screen plates 14, and that the pulsating frequency at the screen will be synchronous with the impulses generated in the pulsating unit. The adjustable control gates 30 insure uniformity of flow to each pulsating compartment beneath the screen deck; and in units of large capacity undesirable dissipation of the impulses may be further prevented by forming the chamber portion 29 so as to provide a siphon effect.

Each of the improved pulsating units 11 shown

in Figs. 1 and 3, consists primarily of a cylinder 32 the displacement chamber 33 of which is in open communication with the distributing chamber portion 29 through the flexible connecting tube 12, and a piston or plunger 34 rapidly reciprocable within the cylinder 32 by any suitable prime mover such as an electric motor 35 co-acting with the piston through a crank or eccentric 36, and variable speed mechanism. While the variable speed motion transmitting mechanism may be of any desired type, the mechanism specifically illustrated in Figs. 1 and 3 comprises a rocking lever or beam 37 having one swinging end 38 connected to the plunger 34 by means of a connecting link 39 and its opposite swinging end provided with a slot 40 while its medial portion is rockably suspended from a fulcrum pin 41 carried by the cylinder 32. The revolving eccentric 36 is pivotally connected to a pivot block 42 by a connecting rod 43, and this block is adjustable along the slot 40 by means of a bell-crank 44 swingably suspended from the fulcrum pin 41 and having one arm connected to the block 42 by a link 45, while its other arm coacts with a manually adjustable screw 46 swingably suspended from the cylinder 32. By turning the screw 46, the bell-crank 44 may be swung in either direction about the pin 41, so as to move the block 42 within the slot 40 in either direction and to thereby vary the stroke of the plunger 34 and hence the amplitude at the pulsations transmitted to the screens through the liquid body 47, and this variation in amplitude can obviously be effected either while the motor 35 is in motion or at rest.

Referring especially to Fig. 6, the modified screening unit 10' shown therein is quite similar in general construction to the unit 10 above described, but the modified unit is provided with a somewhat shallower pulsating chamber 16' and with a considerably deeper liquid discharge siphon section 24' at the end of each of the transverse lower chamber sections or divisions. In this modification, the transverse partitions 23' which are located beneath the screen sections 14, are also extended forwardly through the deep siphon, thereby in fact providing four independent screening devices extending from the distribution chamber 29 to the liquid overflow launder 25. The remainder of the screening unit 10' is the same as the unit 10.

Referring particularly to Figs. 7 to 9 inclusive, the further modified device shown therein embodies a somewhat different screening unit 10'' having a still deeper siphon section 24'', and a pair of modified pulsating units 11'', each of which co-operates directly with a pair of the screen sections 14. In this further modified assemblage of Figs. 7 to 9 inclusive, the housing 13'' of the screens may either be formed integral with the casings 32'' of the pulsators, or connected therewith by means of flexible tubes 12 as in Figs. 1 and 6; and the central partition 23'' should divide both the lower pulsating chamber 16'' and the displacement chamber 33'' into two segregated parts each of which co-operates with two of the screen sections 14. The other two transverse partitions 23'' extend only through the several sub-divisions of the pulsating chamber 16'', but all of these partitions 23'' preferably extend through the deep siphon section 24'' so as to provide four independent siphons. The pulsator units 11'' of this further modification also differ from the unit 11, in that a flexible bellows 34'' is rapidly

reciprocable in each of the chambers 33" formed in the casing 32", and a common electric motor 35" or other prime mover is utilized to simultaneously but oppositely expand and contract the two bellows 34". The stroke of the bellows 34" or the amplitude of pulsation, may be varied by adjusting mechanism similar to that previously explained and co-operating with the lever beam 37", and this modified bellows plunger structure is relatively light and permits more effective packing or sealing of the chambers 33". This modified assemblage is also simpler and more compact than that of Figs. 1 to 4 inclusive, and may also be utilized in multiple as shown in Fig. 5.

Since the normal operation of all of the improved screening devices shown and described herein, is practically the same, it will suffice to describe the operation of the assemblage shown in Figs. 1 to 4 inclusive. During such normal operation of the improved classifier, the prime mover or motor 35 will be operating to rapidly reciprocate the piston 34 and to thereby pulsate the liquid body 47 which fills the displacement chamber 33, tubular connection 12, chamber 29, chamber 16, and siphon section 24, and the liquid level should normally extend slightly above the upper surfaces of the screen sections 14. The raw or untreated material should then be supplied to the feed launder 18 from which it will flow over the weir 19 and upon the screen decks. During advancement of the material along the screen sections 14 and through the upper chamber 15, the entrained particles of granular material or fibre will be repeatedly subjected to pulsatory liquid action by the rise and fall of the liquid through the liquid pervious portions of the screens, and the smaller particles or fibres will pass through the screens and will eventually be discharged with the excess liquid through the siphon section 24 and over the adjustable dams or weirs 26 into the liquid discharge launder 25. The larger particles which are unable to pass through the perforations of the screens will constantly advance across the screen sections 14 and will eventually be delivered into the launder 20 from which they will be discharged through the outlet 21. The material is thus gradually and effectively separated into fine and oversize constituents, and a number of the improved classifying units may be arranged in parallel as shown in Fig. 5 so that all of the fines may be delivered to a common conveyor through the outlet openings 27 of the launders 25. If so desired, a number of the units may be arranged in series so that the separated materials delivered from each unit may be further treated in succeeding units, and the degree of treatment and the quantity of material handled may thus be varied throughout a considerable range by providing a suitable number of the improved screening devices.

While the relatively shallow siphon section 24 may be entirely suitable for certain classes of material, other materials may require the use of a deeper siphon section 24' as shown in Fig. 6, or a still deeper siphon section 24" as illustrated in Fig. 9. The inclination of the bottom 22 of the lower pulsating chamber should also be varied to suit the particular materials being treated, and by utilizing flexible connecting tubes 12 between the screening and pulsating units, the inclination of the screen decks may be varied without affecting the position of the pulsator, and undesirable vibrations will not be

transmitted from the pulsator unit to the screening unit. The functioning of the machine may also be readily controlled by adjusting the vanes 30 and the stroke of the pulsator piston, and these adjustments may be made while the units remain in operation and without interfering with such normal operation.

From the foregoing detailed description it will be apparent that my present invention provides an improved pulsating classifier or screening device which is extremely simple and compact in construction, and which is moreover highly efficient in operation. The improved device can obviously be utilized either singly or in any desired 10 multiple arrangement, so as to effectively classify various kinds of granular or fibrous materials, and is especially useful in the treatment of pulp in the paper industry. The bellows type of plunger reduces the weight of the moving parts 15 to a minimum and also facilitates packing or sealing of the pulsator against leakage, and this type of pulsating unit also facilitates erection and maintenance and may be manufactured at relatively moderate cost. The immersion of these 20 bellows pulsating plungers within the accepted stock chamber, also permits transmission of the pulsations with minimum wave dispersion, and as previously indicated, the flexible connection 12 may be utilized with the bellows type plunger 25 unit as well as with the piston type pulsator. 30 Most efficient distribution of the pulsations within the screening zone may also be effected by adjusting the distribution vanes 30, thereby enhancing the flexibility of the improved assemblages, and the adjustable weirs 26 co-operating 35 with the siphon sections 24 and with the sloping bottoms 22 of the lower chamber 16, enable most efficient delivery of the treated stock without undesirably affecting the pulsations 40 through the screen decks. The present improved classifying device is entirely automatic in operation except for the several adjustments which may however be made without interfering with the normal operation of the machines.

It should be understood that it is not desired 45 to limit this invention to the exact details of construction or to the precise mode of use, herein shown and described, for various modifications within the scope of the claims may occur to persons skilled in the art.

I claim:

1. In combination, an approximately rectangular casing having pulp feed and discharge launders at its opposite ends and a series of partitions between said launders dividing the intervening space into transverse gradually enlarging similar lower chambers having their deeper ends disposed in series along one side of the casing and their shallower ends disposed in like series along the other side of the casing, said casing also having an elongated duct in open communication with all of said shallower chamber ends and a liquid collecting launder extending along its side adjacent to said duct, a series 55 of independent screen plates disposed in approximately the same plane above said lower chambers and coacting with said casing to provide a continuous upper chamber between said feed and discharge launders, a pulsator communicable 60 with the deeper ends of all of said lower chambers and being operable to produce liquid pulsations therein, adjustable gates for varying the flow of pulsating liquid with respect to said lower chambers, and independently adjustable weirs 65 interposed at the shallower ends of said chambers 70 with the deeper ends of all of said lower chambers and being operable to produce liquid pulsations therein, adjustable gates for varying the flow of pulsating liquid with respect to said lower chambers, and independently adjustable weirs interposed at the shallower ends of said chambers 75

between said duct and said liquid collecting launder.

2. In combination, an approximately rectangular casing having pulp feed and discharge launders at its opposite ends and a series of partitions between said launders dividing the intervening space into transverse gradually enlarging similar lower chambers having their deeper ends disposed in series along one side of the casing and their shallower ends disposed in like series along the other side of the casing, said casing also having an elongated duct in open communication with all of said shallower chamber ends and a liquid collecting launder extending along its side adjacent to said duct, a series of independent screen plates disposed in approximately the same plane above said lower chambers and coacting with said casing to provide a continuous upper chamber between said feed and discharge launders, a pulsator communicable with the deeper ends of all of said lower chambers and being operable to produce liquid pulsations therein, means for varying the amplitude of the pulsations produced by said pulsator, pivotally adjustable gates cooperable with said partitions to vary the flow of pulsating liquid with respect to said lower chambers, and independently adjustable weirs interposed at the shallower ends of said chambers between said duct and said liquid collecting launder.

3. In combination, an approximately rectangular casing having pulp feed and discharge launders at its opposite ends and a series of partitions between said launders dividing the intervening space into transverse gradually enlarging similar lower chambers having their deeper ends disposed in series along one side of the casing and their shallower ends disposed in like series along the other side of the casing, said casing also having an elongated duct in open communication with all of said shallower chamber ends and a liquid collecting launder extending along its side adjacent to said duct, a series of independent screen plates disposed in approximately the same plane above said lower chambers and coacting with said casing to provide a continuous upper chamber between said feed and discharge launders, a pulsator communicable with the deeper ends of all of said lower chambers and being operable to produce liquid pulsations therein, a flexible liquid conduit interposed between said pulsator and said casing for permitting variation in the inclination of said plates and said chambers, adjustable gates for varying the flow of pulsating liquid with respect to said lower chambers, and independently adjustable weirs inter-

posed at the shallower ends of said chambers between said duct and said liquid collecting launder.

4. In combination, an approximately rectangular casing having pulp feed and discharge launders at its opposite ends and a series of partitions between said launders dividing the intervening space into transverse gradually enlarging similar lower chambers having their deeper ends disposed in series along one side of the casing and their shallower ends disposed in like series along the other side of the casing, said casing also having an elongated duct the bottom of which is in open communication with the lowermost portions of all of the adjacent shallower chamber ends and a liquid collecting launder extending along its side adjacent to said duct, a series of interchangeably similar independent screen plates disposed above said lower chambers and coacting with said casing to provide a continuous upper chamber between said feed and discharge launders, a pulsator communicable with the deeper ends of all of said lower chambers and being operable to produce liquid pulsations therein, adjustable means for varying the flow of pulsating liquid with respect to said lower chambers, and a flexible liquid conduit interposed between said pulsator and said casing for permitting variation in the inclination of all of said plates and chambers.

5. In combination, an approximately rectangular casing having pulp feed and discharge launders at its opposite ends and a series of partitions between said launders dividing the intervening space into transverse gradually enlarging similar lower chambers having their deeper ends disposed in series along one side of the casing and their shallower ends disposed in like series along the other side of the casing, said casing also having an elongated duct in open communication with all of said shallower chamber ends and a liquid collecting launder extending along its side adjacent to said duct, a series of interchangeably similar screen plates disposed in approximately the same plane above said lower chambers and coacting with said casing to provide a continuous upper chamber between said feed and discharge launders, a pulsator communicable with the deeper ends of all of said lower chambers and being operable to produce liquid pulsations therein, and a series of independently adjustable weirs interposed between said duct and said liquid collecting launder adjacent to the shallower ends of said chambers for varying the point of delivery of liquid from said chambers to said liquid collecting launder.

NEWENHAM A. GRAY.
